UNITED STATES PATENT OFFICE.

GEORGE B. WARNER, OF FITCHBURG, MASSACHUSETTS, ASSIGNEE TO P. T. JACKSON, JR., OF BOSTON, MASSACHUSETTS.

MANDREL FOR PAPER-WINDING MACHINES.

1,076,536.

Specification of Letters Patent. Patented Oct. 21, 1913.

Application filed August 21, 1911. Serial No. 645,282.

To all whom it may concern:

Be it known that I, GEORGE B. WARNER, a citizen of the United States, residing at Fitchburg, in the county of Worcester and State of Massachusetts, have invented an Improvement in Mandrels for Paper-Winding Machines, of which the following description, in connection with the accompanying drawings, is a specification, like letters 10 on the drawings representing like parts.

The invention to be hereinafter described relates to machines for winding paper into tubes or barrels, and more especially to the mandrel on which the paper tube or barrel is formed and its associated parts.

In the formation of paper tubes and barrels, it is desirable that the layers of paper be supplied with an adhesive, at least on one surface and that the layers be wound upon 20 a mandrel or other like device, with sufficient tension to produce a uniform and homogeneous product. For the best results, the mandrel, when in expanded position, should have a continuous and uninterrupted, 25 ed surface, preferably of cylindrical form, and it is desirable at the completion of the tube or barrel formation that means be provided for readily removing the tube or barrel from the mandrel.

The aims and purposes of the present invention are to provide a mandrel that will answer the general considerations above pointed out and to associate the mandrel with appropriate devices, whereby on the 35 completion of the winding operation the completed tube or barrel may be readily removed from the mandrel.

Other and further objects of the invention will appear from the following description 40 in connection with the accompanying drawings embodying one form of the invention, it being understood that the invention in its true scope is definitely defined by the claims.

Figure 1 shows in plan view a sufficient portion of a paper winding machine to make clear the association of the present invention therewith, portions of the frame being shown in section and broken away; Fig. 2 is a side elevation, portions of the frame being broken away; Figs. 3 and 4 are enlarged sections on the line 3-3, Fig. 1; Fig. 5 is a section on the line 5-5 of Fig. 4; Fig. 6 is a section on the line 6-6 of Fig. 3; and Fig. 7 is a section on the line 7-7 of Fig. 4.

The machine frame for sustaining the op-

erating parts of the device may be of any approved character appropriate for the intended purpose, and in the present drawings it is shown as comprising uprights 1, rising from the floor or other support and 60 connected at their top portion by the cross beam 2. Suitably mounted in the machine frame, as graphically indicated in Fig. 1, is the paper guiding roll 3, over which the paper comes from a suitable supply and 65 from which it is drawn to be wound on the mandrel 4.

Suitably supported by the main frame is the main driving shaft 5, said frame being provided with appropriate bearings 6 and 7, 70 Figs. 1, 2 and 3, for said shaft. Loosely mounted upon the driving shaft 5 is the main driving pulley 8, Figs. 1, 2 and 3, which may receive motion from any suitable source of power.

Mounted to slide longitudinally on the shaft 5 between the bearings 6 and 7 is the double cone 9, Figs. 1, 2 and 3, having a circular recess 10 which is engaged by the bifurcated end of an operating arm 11, Figs. 80 2 and 3, said arm being detachably connected to the rod 12 which is mounted in suitable bearings 13, 14, secured to the cross beam 2 of the machine frame, as indicated in Fig. 2. Said operating rod 12 is mounted for longitudinal movement in its bearings 13 and 14 and a spring 15 interposed between a collar 16 secured to said rod and the bearing 13 normally forces the rod 12 to the left, Fig. 2. Secured to the rod in 90 appropriate position for its intended purpose is the sleeve 17 connected by a link 18 to the arm 19 of an operating handle, the construction being such that upon movement of the operating handle to the right, Fig. 2, the rod 12 may be moved longitudinally against the tension of the spring 15 to shift the cone toward the right on the driving shaft 5, all of which will be clearly 95 apparent from Fig. 2.

The present invention contemplates imparting rotative movement to the mandrel through the driving shaft, and under such conditions it is desirable that when the loose pulley 8 is operatively engaged with the shaft the mandrel may be freely rotated thereby, but when the driving pulley 8 is disengaged from operative engagement with the driving shaft, means be provided to quickly bring the mandrel to rest. As one 105

100

105

110

means to the above ends there is secured to the driving shaft adjacent the loose pulley 8, a collar 20 having a flange 21 surrounding a portion of the hub 22 of the driving pulley 8, said collar also having pivoted thereon at 23 an arm 24 for acting upon a friction band 25 to clamp the collar 20 and permit the shaft 5 to the hub of the driving pulley 8. Similarly on the opposite side 10 of the cone 9 there is secured to the shaft 5 a collar 26 having a flange 27 and carrying an arm 28 pivoted at 29, the end of which is adapted to operate a friction band 30 to clamp the same upon the circular portion 31 15 of the bearing 7, the said arm 28 and the arm 24 having their end portions adapted to engage the cone portions on the cone 9, as clearly indicated by Fig. 3.

From the construction thus far described 20 it will be apparent that if the operating rod 12 be moved to the right by hand, Fig. 2, and held in this position by a lock or other device, the arm 24 will cause driving engagement between the loose pulley 8 and the 25 shaft 5 from the friction band 25 and conversely, the arm 28 will release the friction band 30 and permit free rotation of the driving shaft. Similarly when the cone 9 is moved to the left, Fig. 3, the arm 24 will 30 release the loose pulley 8 from driving connection with the shaft 5 and will cause the arm 28 to frictionally bind the band 30 on the circular portion 31 of the bearing 7, thereby affording a frictional resistance to 35 further rotation of the main driving shaft and bringing the same to rest. Obviously, other forms of means may be provided for the above ends, but that described is a convenient form of this feature of the invention. 40

Projecting from the main frame is a bracket or arm 32 below the driving shaft 5, Figs. 2 and 3, and above the shaft 5 is another bracket arm 33, preferably also secured to the bearing 7. Projecting from the bracket arms 32, 33 are the pins or studs 34, which are axially aligned to afford a hinged or pivotal connection with said brackets of a mandrel carrier 35.

50 The mandrel 4 has a head portion mounted in the mandrel carrier as will herein-after more fully appear, and such head portion of the mandrel is connected to the driving shaft 5 by means of a universal joint, the center of movement of said universal joint being in the axial line joining the studs or bolts 34, the construction being such that upon swinging movement of the mandrel carrier 35 on its carrying bolts 55 or studs 34, the mandrel, carried by the carrier, may likewise swing with relation to its operating shaft 5 without being operatively disengaged therefrom.

The mandrel comprises a core 36, Figs. 65 3, 4 and 7 which extends longitudinally

preferably the full length of the mandrel and has a head portion 37, Fig. 3. The head portion 37 of the mandrel has secured thereto a bearing sleeve 38 forming an enlarged head which acts as a rotating support for the mandrel within the mandrel carrier, as indicated in Fig. 3, said sleeve 38 being preferably secured to the mandrel head by means such as the screws 39, Fig. 3. The bearing sleeve 38 has secured to the end portion thereof a cap piece 40, the two parts being preferably, though not of necessity, screw-threaded together as indicated in Fig. 3. The cap 40 may be otherwise secured to the mandrel head, its purpose being to impart through its connection with the driving shaft, rotative movement to the mandrel. 70 75 80

The cap 40 has the arms 41 and the end of the driving shaft 5 has a similar cap or bifurcated device 42, the arms 43 of which, as indicated in Fig. 3, are disposed substantially at right angles to those of the arms 41 of the cap 40. The bifurcated device 42 may be secured to the end of the shaft 5 in any appropriate way as by the pin 44, Fig. 3. Disposed between the ends, the arms of the cap piece 40 and the arms of the bifurcated piece 42, is the usual swivel block 45 constituting a connection between the cap 40 and the bifurcated piece 42 having pivotal connections with each at substantially right angles as usual in the universal or gimbal joint. 90 95

From the construction thus far described it will be apparent that while the mandrel 100 may be driven directly from the driving shaft through the interposed connections described, it may also swing with the mandrel carrier 35, as the latter is moved upon its pivotal supports 34, and the mandrel then take up a position as indicated by dotted lines in Fig. 1. 105

The core 36 of the mandrel is provided with a longitudinal slot, as indicated in Figs. 3 and 7, in which moves the mandrel slide 46, said slide having a series of inclined or wedge portions 47, Fig. 4, adapted to engage and coöperate with similar inclines 48 on a mandrel expander 49 which extends the full length of the mandrel. 110 The number of wedge portions or inclines on the slide and the corresponding inclined portions on the mandrel expander may of course be varied, the essential being that upon longitudinal movement of the mandrel slide 46, the expander 49 may be properly operated. 115

In order to prevent longitudinal movement of the expander, the latter may be provided with slots 50 adapted to engage suitable pins 51, the construction being such that said slots and pins permit in and out radial movement of the expander with respect to the core of the mandrel, but prevent longitudinal movement of the ex- 120 125 130

pander. Secured to the core of the mandrel is a cap piece 52, Fig. 7, between which and the core 36 are hinged the two mandrel sections 53, one at each side of the mandrel, viewing Fig. 7. The upper end portions of these mandrel sections are adapted to engage the expander 49, the construction being such that upon outward movement of the expander 49, the mandrel sections 53 will be drawn outwardly on their pivotal connection with the core and cap, as heretofore pointed out.

From the construction thus far described it will be noted that the mandrel 4 comprises a core portion extending longitudinally of the mandrel and having a head 37 projecting from one end thereof, and that said head forms appropriate means for sustaining the mandrel in the mandrel carrier 35.

When the mandrel is in operative relation with the driving pulley 8, it is desirable that it be in expanded condition, and that its end opposite the driving shaft 5 be properly supported. As one means to this end the present invention contemplates a bracket 54, Figs. 1 and 2, secured to the machine frame 1, said bracket having a guideway for a slide block 55, Figs. 1, 2 and 5, which is held in its guided position by means of the flanges 56, as best shown by Fig. 5. Extending longitudinally through the slide block 55 is a shaft 57, see Figs. 4 and 5, one end of which carries the mandrel supporting cap 58 and the other end of which has the enlarged nut or head 59, the construction being such that while the shaft 57 may rotate in the slide block 55, it is confined to longitudinal movement with said slide block. Disposed between the end of the slide block 55 and the cap portion 58 are suitable anti-friction rollers 60, Fig. 4.

In order that the slide block 55 may be conveniently moved to cause the cap 58 to engage or disengage the end of the mandrel, said block is connected by a link 61 to the short arm 62 of a bell crank lever comprising the handle 63, said link 61 being pivoted to the block at 64, all as clearly indicated in Fig. 1 and the construction being such that upon movement of the handle 63 from the full to the dotted line position, Fig. 1, the slide block 55, and therefore the cap 58 will be moved away from the end of the mandrel, and conversely, upon movement of the handle 63 in the reverse direction the cap 58 will be caused to engage the end of the mandrel, and by acting upon the end of the slide 46 to cause said slide to move to the right against the action of the slide spring 65, as indicated in Figs. 3 and 4, it being understood that the slide spring 65 at the right end of the mandrel, Fig. 3, acts normally to move the slide 46 to the left to permit the mandrel expander to move radially inward,

and that the left end of the slide 46 projects at such times, somewhat beyond the end of the mandrel.

From the construction thus far described it will be noted that if the mandrel be in the dotted line position, as indicated in Fig. 1, it will be contracted, that is, the slide 46 will be held to the left or in a direction to permit the expander 49 to move radially inward, the end of the slide at such times being somewhat beyond the end of the mandrel. If now the mandrel be moved into full line position, Fig. 1, and the slide block 55 be moved to cause the cap 58 to engage the end of the mandrel, said cap will first cause the slide 46 to move to the right against the action of the spring 65 and thus expand the mandrel into its desired dimension for receiving the paper.

Inasmuch as the paper is wound upon the mandrel with considerable tension and inasmuch also that the winds of paper may bind upon the mandrel, it is desirable that means may be provided so that when the mandrel is swung from its full to its dotted line position in Fig. 1, the paper tube or barrel may be readily pulled or removed longitudinally therefrom. As one means to this end the invention contemplates the following mechanism, as indicated more clearly in Figs. 1 and 2. Pivottally mounted at 66, Fig. 1, on a bracket 67 secured to the mandrel carrier 35 is a handle 68. Surrounding the mandrel at the end thereof adjacent the mandrel carrier is a ring 69 which is operatively connected with the handle 68 for movement longitudinally of the mandrel. As one means of connecting the ring 69 to the handle 68 said ring may be provided with pins 70 diametrically disposed and projecting into suitable sockets of the encircling portion of the handle 68, as clearly indicated in Figs. 1, 2 and 3, the construction being such that when the handle 68 is moved to the left, the ring 69 will be caused to move longitudinally of the mandrel and engage the end of the paper tube or barrel 71, Figs. 1 and 2, and detach it from any adherence upon the surface of the mandrel so that it may be readily pulled off by hand when the mandrel is swung to its outer or dotted line position, as indicated in Fig. 1. The handle 68 projects to the front of the machine, as indicated in Figs. 1 and 2, and the ring 69 normally rests, as indicated by full lines in Figs. 1 and 3, close up against the flange 72 of the bearing sleeve 38 to which the head of the mandrel is secured.

From the construction thus far described it will be apparent that when the mandrel is moved into the position shown by full lines in Figs. 1 and 2, and the cone 9 is moved to the right, the driving shaft, and therefore the mandrel, will be properly rotated to wind the paper upon the mandrel,

the latter being at such time in its fully expanded position. Upon completion of the winding operation the handle 63 will be moved to the left, Fig. 1, whereupon by force applied to the handle 68, the mandrel may be swung into the dotted line position. The mandrel having been swung to the dotted line position, as indicated in Fig. 1, the handle 68 may be moved to the left to thereby carry the ring 69 longitudinally of the mandrel to detach the tube or barrel therefrom. Owing to the ring sliding longitudinally of the mandrel, the end of the tube or barrel only is engaged thereby and by appropriate force applied to the handle 68 said tube or barrel may be slid longitudinally of the mandrel as the latter is at this time in contracted condition, all as will be clearly understood from the foregoing.

20 While the detailed mechanism hereinbefore described and as shown in the drawings constitutes a convenient form of the present invention for carrying the latter into practical effect, it is to be understood that the invention is not circumscribed by such details but that they may be variously changed as to the form and general character within the true scope of the invention as pointed out by the claims.

30 It may at times be desirable that when swinging the mandrel from its dotted to its full line position, Fig. 1, means be provided to indicate when the free end of the mandrel is in proper position to be engaged by the cap 58 and to this end a stop may be employed to engage one of the flanges of the mandrel carrier as the latter and the mandrel swing backward into full line position, Fig. 1. Such stop is indicated at 73, Fig. 40, wherein it is shown as an adjustable screw bolt threaded into the socket piece 74 and the end of said bolt adapted to engage with the flange 75 of the mandrel carrier as the latter and the mandrel reach their final operative position in the machine. It will be noted also from the construction hereinbefore described as one embodiment of the invention that the handle 68 not only serves as means for detaching the paper tube or barrel from the mandrel, but also serves as a means for moving the mandrel and the mandrel carrier about the pivotal connections of those parts of the frame to place the mandrel in position for removing the 55 tube or barrel from the mandrel.

What is claimed is:—

1. In a machine for winding paper into tubes or barrels, the combination of a driving shaft, a mandrel operatively connected to and operated by said shaft, a mandrel expanding device, a mandrel carrier pivotally connected to the machine frame and carrying said mandrel to permit one end thereof to be swung away from the machine for removal of the paper tube or bar-

rel lengthwise therefrom while still maintaining the operative connection between said mandrel and driving shaft, means to operate the mandrel expanding device to permit concentration of the mandrel as it is so swung, and means for swinging the mandrel transversely of the shaft and detaching the paper tube or barrel therefrom. 70

2. In a machine for winding paper into tubes or barrels, the combination of a driving shaft, a mandrel carrier pivotally connected to the machine frame to swing transversely of said shaft, a mandrel having a head mounted in said carrier, and driving connections between the mandrel and said shaft permitting the mandrel to be swung outward with the carrier while maintaining the said mandrel in operative relation with said shaft. 75

3. In a machine for winding paper into tubes or barrels, the combination of a driving shaft, a mandrel carrier pivotally connected to the machine frame to swing transversely of said shaft, a mandrel having a head mounted in said carrier, driving connections between the mandrel and said shaft permitting the mandrel to be swung outward with the carrier while maintaining the said mandrel in operative relation with said shaft, and means for detachably holding the end of the mandrel opposite said mandrel carrier. 85

4. In a machine for winding paper into tubes or barrels, the combination of a driving shaft, a mandrel carrier pivotally connected to the machine frame to swing transversely of said shaft, a mandrel having a head mounted in said carrier, driving connections between the mandrel and said shaft permitting the mandrel to be swung outward with the carrier while maintaining the said mandrel in operative relation with said shaft, and means movable longitudinally of the mandrel for detaching the paper tube or barrel from the mandrel. 100

5. In a machine for winding paper into tubes or barrels, the combination of a mandrel having a head projecting at one end of the mandrel, a mandrel carrier in which said mandrel head is rotatably mounted, a driving shaft, driving connections between the mandrel head and driving shaft for rotating the mandrel and which permits of the mandrel being swung outward with the carrier while maintaining the mandrel in operative relation with said shaft, and pivotal connections between the mandrel carrier and frame of the machine permitting it and the mandrel to be swung relatively to said shaft. 110

6. In a machine for winding paper into tubes or barrels, the combination of a mandrel having a head projecting at one end of the mandrel, a mandrel carrier in which said mandrel head is rotatably mounted, a driving shaft, connections between the man- 125

- drel head and driving shaft for rotating the mandrel, pivotal connections between the mandrel carrier and frame of the machine permitting it and the mandrel to be swung relatively to said shaft, a ring mounted on the mandrel, and a single or unitary device for swinging the mandrel outward and moving said ring longitudinally of the mandrel for removing the tube or barrel from the mandrel when it is so swung. 5
7. In a machine for winding paper into tubes or barrels, the combination of a collapsible mandrel having a head projecting from one end of the mandrel, a driving shaft, driving connections between the head of the mandrel and said driving shaft, a mandrel carrier in which said mandrel head is rotatably mounted, said mandrel carrier being pivotally mounted on an axis intersecting the axis of said driving shaft and adapted to swing laterally, and means actuated as the mandrel and carrier are swung outward to permit the mandrel to be collapsed. 10
8. In a machine for winding paper into tubes or barrels, the combination of a collapsible mandrel having a head projecting from one end of the mandrel, a driving shaft, driving connections between the head of the mandrel and said driving shaft, a mandrel carrier in which said mandrel head is rotatably mounted, said mandrel carrier being pivotally mounted on an axis intersecting the axis of said driving shaft and adapted to swing laterally, means actuated as the mandrel and carrier are swung outward to permit the mandrel to be collapsed, and means movable longitudinally of the mandrel to detach the paper tube or barrel therefrom. 20
9. In a machine for winding paper into tubes or barrels, the combination of a mandrel carrier pivotally mounted on the machine frame, a mandrel having a head projecting at one end and rotatably mounted in said mandrel carrier, a driving shaft, universal joint driving connections between the mandrel head and said shaft disposed in the pivotal axis of the mandrel carrier adapting said mandrel and carrier to be swung laterally, and means actuated as the mandrel carrier and mandrel are swung outward to permit collapse of the mandrel. 25
10. In a machine for winding paper into tubes or barrels, the combination of a mandrel carrier pivotally mounted on the machine frame, a mandrel having a head projecting at one end and rotatably mounted in said mandrel carrier, a driving shaft, universal joint driving connections between the mandrel head and said shaft disposed in the pivotal axis of the mandrel carrier adapting said mandrel and carrier to be swung laterally, means actuated as the mandrel carrier and mandrel are swung outward to permit collapse of the mandrel. 30
11. In a machine for winding paper into tubes or barrels, the combination of a driving shaft, a mandrel carrier pivotally connected to the machine frame to swing transversely of said shaft, a mandrel having a head mounted in said carrier, driving connections between the mandrel and said shaft permitting the mandrel to be swung outward with the carrier while maintaining the said mandrel in operative relation with said shaft, and a stop to limit the inward swing of the mandrel. 70
12. In a machine for winding paper into tubes or barrels, the combination of a collapsible mandrel having an enlarged head portion projecting from one end of the mandrel, a mandrel carrier pivotally connected to the machine frame and having a bearing portion for rotatably supporting the enlarged head portion of the mandrel, means for detachably connecting the head portion of said mandrel and bearing of the mandrel carrier, a driving shaft, and connections including as a part thereof a universal joint between the driving shaft and head of the mandrel to permit the mandrel to be swung outward from the machine while maintaining uninterrupted driving connection with the driving shaft. 80
13. In a machine for winding paper into tubes or barrels, the combination of a driving shaft, a collapsible mandrel alined with said shaft when in winding position, driving connections between the mandrel and shaft, a mandrel carrier having a bearing portion for rotatably supporting one end of the mandrel, pivotal connections between the mandrel carrier and machine frame to permit the mandrel carrier and mandrel to be swung outward from the machine, a longitudinal bearing for the opposite end of the mandrel, and means to expand the mandrel by longitudinal movement of said bearing. 90
14. In a machine for winding paper into tubes or barrels, the combination of a driving shaft, a collapsible mandrel alined with said shaft when in winding position, driving connections between the mandrel and shaft, a mandrel carrier having a bearing portion for rotatably supporting one end of the mandrel, pivotal connections between the mandrel carrier and machine frame to permit the mandrel carrier and mandrel to be swung outward from the machine, a longitudinal bearing for the opposite end of the mandrel, means to expand the mandrel by longitudinal movement of said bearing, and means operating when the free end of the mandrel is swung outward to permit collapse of the mandrel. 115

15. In a machine for winding paper into tubes or barrels, the combination of a driving shaft, a collapsible mandrel aligned with said shaft when in winding position, driving connections between the mandrel and shaft, a mandrel carrier having a bearing portion for rotatably supporting one end of the mandrel, pivotal connections between the mandrel carrier and machine frame to permit the mandrel carrier and mandrel to be swung outward from the machine, a longitudinal bearing for the opposite end of the mandrel, means to expand the mandrel by longitudinal movement of said bearing,

means operating when the free end of the 15 mandrel is swung outward to permit collapse of the mandrel, and a ring mounted at one end of the mandrel for detaching the paper tube or barrel when the mandrel is swung outward.

20 In testimony whereof, I have signed my name to this specification, in the presence of two subscribing witnesses.

GEORGE B. WARNER.
